TELEPHONE SYSTEM

Reinhold Hoefert and Eduard Wochinger, Berlin, Germany, assignors to Siemens & Halske Aktiengesellschaft, Siemensstadt, near Berlin, Germany

Application October 14, 1932, Serial No. 637,748
In France October 19, 1931

10 Claims. (Cl. 179—27)

The invention relates to a circuit arrangement for telephone systems and has for its object to facilitate connecting traffic between semi-automatic and completely automatic exchanges. According to the invention, the connecting traffic is carried out in the following manner:

In semi-automatic traffic a calling subscriber has access over automatically set numerical impulse receivers to an exchange operator who, according to requirement, completes the connection in the required traffic direction over the connecting route over which she was called either to a subscriber of a completely automatic exchange or another subscriber of a semi-automatic exchange. The connecting route over which the exchange operator passes the call can be used in completely automatic traffic also and in such a case the setting of the numerical impulse receiver in this connecting route is controlled from the completely automatic exchange.

An embodiment of the invention is shown in Figs. 1-3 of the drawings wherein Fig. 1 shows a general plan diagrammatically whereas the individual circuits associated with the repeater Ue are illustrated in Fig. 2 and those associated with the group selector IGW in Fig. 3.

The features of the invention will first be described in conjunction with Fig. 1 of the drawings.

30 When, for example, a subscriber T5 of the local battery exchange OB1 lifts his receiver, a call finder AS commences to operate in known manner to which, after completed operation, an assessor Ab is set. Over this assessor access is made to the repeater Ue which causes a secondary line switch MW to be set to an idle group selector IGW in the automatic exchange SA1. The group selector IGW is automatically raised to the first level in which it hunts freely for an idle operator's position VPL. The exchange operator at this position is notified of the call by the signal lamp lighting up, whereupon she connects herself to the calling subscriber and inquires for the number required. She is also in a position to recall said subscriber in known manner in case he, in the meantime, has replaced his receiver.

If the calling subscriber then requires a connection with, for example, a subscriber of the automatic exchange SA1, the operator after having inserted the connecting plug in the appropriate jack causes the group selector and the numerical impulse receiver succeeding said group selector to be set in a manner of no interest in the present case.

Should the subscriber, however, require a connection with, for example, the subscriber T4 of the automatic exchange SA2, she transmits impulses over the line over which she was called. The first impulse series which corresponds to the identification digit for the junction line seize for the call is then suppressed due to the fact that the operator is already connected to this line. The second impulse series, however, influences the group selector GW in the automatic exchange SA2 accessible over the repeater Ue. This group selector is set in known manner to an idle final selector, for example, LW, which in turn is ultimately set to the required subscriber's line by means of additional impulse series transmitted by the operator.

In the case of the calling subscriber requiring a connection with the subscriber of his own local battery exchange, for example, the subscriber T6, the impulse series denoting this line causes the group selector GW in the local battery exchange OB1 to be influenced, which in turn obtains access to a final selector LW capable of being set to the required T6-subscriber's line by the succeeding impulse series transmitted by the operator.

The calling subscriber T5, however, has also access to subscribers of other local battery exchanges (for example, OB2) and is able to set the group selector GW in the local battery exchange OB1 to a junction line leading to the local battery exchange OB2 by transmitting a corresponding impulse series. A plurality of local battery exchanges also are accessible in succession over the individual numerical impulse receivers in a similar manner.

If a subscriber of the automatic exchange SA2, for example, T3, now calls instead of a subscriber of a local battery exchange, he has access over the free hunting selecting switches (call finder AS and change-over switch UW) to an idle junction line leading to the automatic exchange SA1 which may, for example, be represented by the line shown in Fig. 1 leading to the group selector IGW, that is to say the line accessible when a local battery exchange subscriber calls. This group selector is not set automatically as in the case of local battery subscriber calling but has to be raised to the required level by means of impulses transmitted by the calling subscriber. If, for example, a subscriber of the automatic exchange SA1 (T2) is wanted, the group selector IGW is raised to the second level, whereupon, by means of additional impulse series, the group selectors IIIGW and IIIIGW and finally the final

selector LW may be set to the required subscriber T2.

Should, however, the subscriber T3 not want a subscriber of this automatic exchange but, for example, a subscriber of his own automatic exchange (SA2), he transmits another impulse series which, by means of the discriminator ML (also actuated by the numerical impulses), causes the switch UW to operate so that it sets its wiper to a line leading to the group selector GW in the automatic exchange SA2. The calling subscriber T3, by transmitting further impulse series, is then in a position to cause the group selector to be raised to the second level in which it hunts for an idle final selector LW in the automatic exchange SA2 which then in turn may be set to the required T4-subscriber's line by means of additional impulse series.

The subscriber T3 is able to obtain a direct connection with a subscriber of a local battery exchange, for example, OB1. After having caused the switch UW to operate, he sets the group selector GW by means of a corresponding impulse series to a line leading to the repeater Ue, whereupon the line, otherwise used for calling an operator, can be utilized for calls in opposite direction. Similarly to the manner in which an operator assists in setting up a connection and described above, the numerical impulse receivers in the rural exchange OB1 or in further succeeding rural exchanges, such as OB2, can then be influenced by additional impulse series.

From this general description it will be seen that a calling subscriber of a local battery exchange has access to an operator's position over a group selector automatically set to an idle operator and located in an automatic exchange. This connecting route used for calling can, however, as indicated above also be utilized for automatic connections from subscribers of automatic exchanges in which case the group selector IGW is not set automatically but hunts for the required level under the influence of numerical impulses transmitted by the calling subscriber.

The connecting route used for calling can be likewise utilized in this manner for definite connections in the opposite traffic direction.

Having now described the various switch trains in general, the switching operations performed in the individual circuits—that is to say, those of the repeater Ue and the group selector IGW—will now be described in conjunction with Figs. 2 and 3 of the drawings.

Assuming that when a subscriber of the local battery exchange calls in the ordinary manner, the assessor Ab shown diagrammatically in Fig. 1 has been set to the calling rural exchange, relay A1 shown in Fig. 2 is energized in a manner of no interest in this case over the a-lead, contact 70sp, winding III and earth. This relay is first placed in a locking circuit extending over contacts 76a1, 73c and winding II. If the connecting route is prepared for use—that is to say, on the condition that all the devices are at normal—a locking circuit for relay A1 over winding I and also an energizing circuit for relay C are simultaneously closed over contact 76a1 and the wiper z1 of the time switch Z. Winding II of relay A1 is then disconnected at contact 73c. The closing of contact 69c causes relay Sp to operate over earth, relay Sp, contact 69c, resistance W12, battery, earth. Winding III of relay A1 also is then disconnected at contact 70sp. The closing of contact 46c energizes relay

An over: earth, contacts 45a1, 46c, 47q, relay An, battery, earth. Relay R operates in the following circuit on the closing of contact 55an: earth, contacts 42p, 56an, 51d, relay R, battery, earth. Due to the closing of contact 52r the rotary magnet D of the secondary lineswitch MW receives an impulse which causes said secondary lineswitch to advance one step. Relay R is deenergized on the energization of the rotary magnet D due to the opening of contact 51d and disconnects the rotary magnet D by opening its contact 52r. Relay R is then connected up afresh and the secondary lineswitch MW is continuously advanced due to the interaction between the rotary magnet D and relay R until it reaches an idle connecting device shown in Fig. 3. When this occurs, the undermentioned circuit is closed, since relay Ro is energized over windings I and II of relay Ao (without, however, influencing this relay) when said connecting device is in its normal position and contact 95ro, consequently, is closed: earth, contact 31an, windings II and I of relay P, wiper of the secondary lineswitch MW, contact 95ro, relay Co, winding I of relay Ro, battery, earth. Relays P, Co, and Ro operate in this circuit.

Due to the opening of contact 48p on the energization of relay P, relay R remains deenergized with the result that the secondary lineswitch MW cannot be further advanced. The speaking leads are switched through to the connecting device of Fig. 3 at contacts 23p and 24p. The following circuit is then closed: earth, contacts 26q, 21an, 23p, wiper of the secondary lineswitch MW, windings I and II of relay Ao, battery, earth. The closing of contact 199ao in Fig. 3 causes an impulse to be transmitted to the vertical magnet HGW over: earth, battery, vertical magnet HGW, winding III of relay Po, rotary off-normal contact 192wgw, contact 199ao, 99b, earth. The group selector IGW is then raised to the first level. Due to the slow-acting relay Q being energized some little time after the closing of contact 49p, the momentary current applied to relay Ao is cut off at contact 26q, causing this relay to relapse. In addition, the vertical magnet and also winding III of relay Po located in the circuit for said vertical magnet are now deenergized so that consequently impulses are transmitted to the rotary magnet DGW of the group selector over: earth, battery, rotary magnet DGW, off-normal contact 98kgw (closed after the first vertical step), contact 114po, relay interrupter RU, earth. The group selector IGW now hunts freely in the first level for an idle trunk to the operator's position VPL. On finding this, relay Po is energized over windings I and II in known manner, whereupon contact 114po is opened so that the group selector is brought to rest. The seized operator's position is guarded by winding II of relay Po being short circuited over contact 104po. The operator's position seized by the group selector IGW is not shown in this case. A call signal can be produced at the operator's position, for example over the b-lead and relay E shown in Fig. 2 (without, however, energizing this relay), while the subscriber can receive an exchange signal from the operator's position indicating that he has been connected to such a position.

When the exchange operator now inserts the enquiry plug, relay I which is connected to the a-lead (Fig. 2) is energized due to a potential being applied. The energization of relay I causes relay Do and D1 to operate over contact 2i. The exchange operator is then switched through to the

calling subscriber by the closing of contacts 32do and 29i. If the subscriber in the meantime has replaced his receiver, the operator can recall him in known manner by a definite switching operation. If he has awaited the operator's reply, however, said operator inquires for the number required and then completes the connection by transmitting impulses corresponding to the required traffic direction.

10. If, for example, the calling subscriber wishes to set up a connection with a subscriber of the local battery exchange OB1 shown in Fig. 1, the first impulse series is suppressed due to the fact that the exchange operator is already connected 15 to the junction line to be used for the connection. On the first deenergization of relay I during the impulse transmission, relays V and VI only are caused to operate over: earth, contacts 3i, 4d1, relay V, windings II and I of relay VI, battery, earth. Relays Do and D1 remain energized over contact 1do during this first impulse series. After 20 relay VI has been energized during the first impulse series, relay K is influenced over earth, battery, winding II of relay K, contact 25v1, 12u, 25 17do, 18s, 19a1, earth, and the calling subscriber, therefore, is disconnected due to the opening of contacts 72k and 57k. At the end of the first impulse series, that is to say on the prolonged 30 energization of relay I with consequent deenergization of relays V and VI, relays P1 and L are caused to operate over the following circuit due to relay K remaining energized over its contact 11k: earth, battery, relay L, winding II of relay P1, cam contact of a stepping switch A, contacts 14v1, 15k, 17do, 18s, 19a1, earth. The closing of contact 64p1 causes the group selector GW in the automatic exchange SA2 shown in Fig. 1 to be seized. A circuit for the setting of this group selector is prepared over contact 55p1.

40. When the operator now transmits the second impulse series which may comprise four impulses, relay I is deenergized a number of times corresponding to the number of impulses transmitted and causes relay V and VI to remain energized 45 during the whole impulse series. Due to relay L now being energized (earth, battery, L, 26t, 27v, earth) the rotary magnet A of a stepping switch is intermittently influenced over earth, contacts 3i, 7l, switch magnet A, battery, earth. Consequently the wiper a of this stepping switch is advanced four steps. Over contact 56i the impulses for the setting of the group selector GW are transmitted, causing this group selector to be 50 raised to the fourth level.

55. At the end of the impulse series—that is to say, when relay I remains energized an extended period—relays V and VI as well as the switch magnet A are deenergized due to the opening of contact 3i. Relay U will now operate over earth, battery, relay U, switch wiper a, contacts 14v1, 15k, 17do, 18s, 19a1, earth. Relay U is placed in a locking circuit over its contact 13u. The opening of contact 12u deenergizes relay K after 60 relay P1 has released due to the opening of the cam contact a1—11 and relay L also has relapsed due to contact 27v being opened. The set group selector is released on the opening of contact 64p1. The closing of contacts 72k and 57k 65 switches through the junction line with the result that the succeeding impulse series can influence, for example, the group selector GW in the local battery exchange OB1 shown in Fig. 1. By means of further impulse series the connection to a subscriber of this local battery exchange 70

or to a subscriber of another rural exchange (for example OB2) can then be completed.

Ringing current is transmitted to the required subscriber in known manner of no interest in this case (automatically or by the assistance of an operator) after the connection has been set up. When the called subscriber answers, the exchange operator withdraws the connecting plug and this causes relay I to release. Consequently, relay V and VI are reenergized over contact 3i. 10

Due to this energization, however, lasting an extended period, relay Do is caused to relapse due to the short circuit over contact 6v which in turn causes relay D1 to be deenergized in consequence of contact 1do being opened, thus causing the release of relays V and VI. Prior to the release of relay D1 the switch magnet Z receives an impulse over earth, battery, switch magnet Z, contacts 11do, 18d1, earth. This switch therefore executes a switching step and closes its cam 20 contact denoted by Z1—11.

It should be mentioned in this connection that all the contacts characterizing an open circuit comprise mechanically operated cam contacts and are set in the operative position indicated by 25 the index. Contacts characterized by a closed circuit are only intermittently actuated on the energization of the corresponding switch magnet.

After the first switching step, on the part of the stepping switch Z, as stated above, the cam 30 contact z1—11 is closed. Relays C and A1 relapse after the first switch step (switch wiper Z1). Contact 84z, actuated on the first energization of the switch magnet Z, causes relay R1 to operate over earth, contact 86s, 84z, relay R1, resistance 35 Wi3, battery, earth. The switch magnet Z therefore is deenergized after the first switch movement due to contact 80r1 being opened. Contact 84s also now being opened causes relay R1 to release so that a fresh circuit is closed for the 40 switch magnet Z as follows: earth, battery, switch magnet Z, contact 80r1, cam contact z1—11, earth. An interaction between the switch magnet Z and relay R1 is therefore set up which continues until the stepping switch Z 45 has been restored to its normal position and in this position reopened the cam contact z1—11. In the meantime relay U relapsed due to the opening of contacts 17do and relay Sp by contact 69c being opened. The stepping switch A, all 50 the cam contacts a1—11 of which also are closed, is restored to normal on the advance operation of the part of the stepping switch Z over contact 8s. When relay I releases on the connecting plug being withdrawn, relay P relapses before the release of relay D1 (short circuit over contacts 115i and 116d). The locking circuit for relays Co and Ro is consequently opened at contact 36p (Fig. 3). Relay Co being a slow acting relay remains energized a little while longer so that 60 over contacts 97co and 96ro the primary winding of the transformer Tr receives an impulse the voltage of which is raised to such an extent that the neon lamp is lighted and relay B is influenced over the secondary winding and contacts 94co and 93ro in the group selector IGW. Winding II of relay Ao is influenced over contact 111b and the close rotary off-normal contact 113wgw, causing relay Po to relapse due to the opening of contact 103ao. The group selector 65 by the energization of its rotary magnet DGW over contact 114po is then advanced to its normal position. The opening of the rotary off-normal contact 113wgw deenergizes winding II of relay Ao and cuts off relay B at contact 109ao. 70

75

The connecting device shown in Fig. 3 is thus also restored to normal. The connecting route utilized for calling is now completely released and the speaking connection extends over the 5 rural exchange only. The release of the connection can be effected in any known manner.

If the calling subscriber wishes to set up a connection with, for example, the subscriber T_e of the automatic exchange SA_2 , the operator transmits 10 the second impulse series comprising two impulses—the first impulse series being suppressed as stated above. This causes the group selector to be set in known manner. Due to the fact that relay U is not energized the group selector remains 15 in the set position and additional impulse series influenced the final selector LW shown in Fig. 1 found by the group selector GW to be idle. The subscriber T_e is then called in known manner. When he answers, a negative potential is 20 applied to the b -lead in a manner of no interest in the present case and this negative potential causes relay Y_1 to be influenced over: earth, relay Y_1 , contact $44e$, b -lead and negative potential in the succeeding switch. The closing of contact 25 $90y_1$ causes relay S to operate over: earth, battery, relay S , contact $90y_1$, $89p_1$, earth. Relay S is placed in a locking circuit over contact $88s$ and the group selector is maintained in the set 30 position over contact $65s$. Relay I is again de-energized when the connecting plug is withdrawn, whereupon the connecting route leading to the exchange operator over the secondary lineswitch MW is released in the manner indicated above. 35 The stepping switch Z , however, is not alone advanced into its original position under the influence exerted by relay R_1 but a thermo relay Th also is influenced with the result that the stepping switch Z takes a considerably longer time to advance (for example, six minutes). When relay 40 I is deenergized on the withdrawal of the connecting plug, the stepping switch Z receives an additional impulse which causes said stepping switch to advance one step. In the meantime, however, the thermo relay Th has been influenced and 45 starts operating after a short delay, causing relay R_1 to operate over contact $87h$ and the energizing circuit for the switch magnet Z to be cut off at contact $89r_1$. The thermo relay Th is released on the opening of contact $83r_1$ and thereupon, 50 after a short interval, opens its contact $87h$ so that relay R_1 , consequently, relapses. The switch magnet Z then again receives an impulse over contact $80r_1$ and takes a further step whereupon the thermo relay Th is influenced afresh over 55 contact $83r_1$. This interaction between the switch magnet Z , the thermo relay Th and relay R_1 continues until the stepping switch (switch wiper $ZIII$) has reached a definite position in which relay Y_1 is short circuited over contact 60 $45a_1$. The opening of contact $90y_1$ causes relay S to release, thus releasing the group selector GW and cutting off further switch trains due to the opening of contact $65s$. The stepping switch Z 65 is now restored to normal under the control of relay R_1 in known manner and thereby causes the stepping switch A also to be restored to normal so that the complete system is set at normal after all the connecting devices have thus been forcibly cut off.

If now, for example, the subscriber T_3 of the automatic exchange SA_2 is calling instead of a subscriber of a local battery exchange, the former will be switched through to the first group selector IGW over the call finder and the changeover

switch in the manner indicated in Fig. 1. The connecting device shown in Fig. 3 is then seized in a similar manner, with the difference, however, that no potential is applied to the a -lead for the purpose of causing relay A_0 to operate with the result that the vertical magnet of the group selector does not receive an impulse. Such a potential is not applied until the subscriber starts dialling and thereby causes the group selector IGW to be set in accordance with the impulses transmitted. 10 The impulses transmitted for the setting of the group selector at the same time influence a discriminator switch ML diagrammatically shown in Fig. 1. If the impulse series transmitted corresponds to another traffic direction than that over 15 which the seized group selector is accessible, the switch UW is so switched over in a manner of no interest in this case that it hunts for an idle group selector in the automatic exchange SA_2 . When access has been found to such a group selector, for 20 example the group selector GW , the calling subscriber himself is in a position to influence this switch and cause it to be set either to a final selector LW or to the repeater U_e . After the group selector has been set to a repeater in the 25 manner indicated in Fig. 2, an earth potential applied in a manner of no interest to the c -lead causes relay C to operate which by closing contact $59c$ in turn causes the energization of relay S_p and consequently the disconnection of relay A_1 . 30 The potential applied to the a -lead over contacts $62c$ and $63p_1$ influences the local battery exchange (OB_1) relay which corresponds to relay I shown in Fig. 2. When the calling subscriber now transmits impulses—that is to say, when he influences 35 relay I over the a -lead, the energizing circuit for this relay is intermittently interrupted so that the relay in the local battery exchange corresponding to relay I is intermittently deenergized and this impulse receiving relay in the local battery exchange then causes the further switch train to be completed in known manner. After access has been found to the required subscriber ringing current is automatically transmitted to him so that the required speaking connection is completed 40 when the called subscriber answers.

As will be seen from the description, the group selector IGW is automatically set when seized by a subscriber of a local battery exchange but this automatic setting does not take place when a subscriber of an automatic exchange calls. For a subscriber of such an exchange to influence the group selector a special impulse series has to be transmitted. 50

Furthermore, it has been stated that the connecting route over which a local battery exchange subscriber calls an operator is automatically used by subscriber of automatic exchanges for the setting up of connections to other automatic exchange subscribers as well as to subscribers of a 55 local battery exchange. In the latter case a special impulse reversal takes place (relay I receives earth impulses and transmits potential impulses).

What is claimed is:

1. In a telephone system, two automatic offices and a semi-automatic office, a trunk line connecting the two automatic offices, a trunk line connecting one automatic office and the semi-automatic office, subscribers' lines terminating at the offices, means automatically operated responsive to the initiation of a call on a line terminating at said one automatic office for extending a connection to the other automatic office over the first trunk line, and means automatically operated responsive to the initiation of a call on a line termi- 70 75 78 80 85 90 95 98 99

nating at the semi-automatic office for extending a connection from the line through said one automatic office to the other automatic office over the two trunk lines in series.

5 2. A telephone system as claimed in claim 1 in which connections extended from lines terminating at the automatic office are further extended under directive control of the calling party and in which calls extended from lines terminating at the semi-automatic office are further extended by an operator at the terminating automatic office.

10 3. A telephone system as claimed in claim 1 in which different conditions are imposed on the trunk line connecting the two automatic offices dependent upon the office at which the involved line terminates.

15 4. In a telephone system, a trunk line terminating in an automatic switch having a primary movement in one plane and a secondary movement in an intersecting plane, two means of access to said trunk, means for directly operating said switch in its primary movement over one means of access, means for automatically operating said switch in its secondary movement in response to the completion of its primary movement, and means automatically responsive to the extension of a call to said trunk over said other means of access for automatically operating the switch in both its primary and secondary movements.

20 5. In a telephone system, two offices, an operator's switchboard, a trunk connecting said offices, subscribers' lines terminating at said offices, means responsive to the initiation of a call on a line terminating at one office for extending a connection from the line to the switchboard via said trunk, switching apparatus at said one office reversionally controlled over the trunk from the switchboard for further extending the connection from the calling line to a called line terminating at said one office, and means whereby a calling party on a line terminating at the other office is enabled to directly control said switching apparatus to extend a connection from that line to a called line in said one office.

25 6. In a telephone system, subscribers' lines terminating at each office, a trunk line connecting the first and second offices, three branches for the trunk line at the second office, a second trunk line connecting the second and third offices, means for establishing a connection from a line in the first office to a line in the third office over the first trunk line, its first branch and the second trunk line, means for establishing a connection from a line in the first office to a line in the second office over the first trunk line and its second branch, and means for establishing a connection from a line in the second office to a line in the first office over the first trunk line and its third branch.

30 7. A telephone system as claimed in claim 6 in which connections from a line in the first office to lines in the second and third offices are completed under control of an operator at the third office

and in which a connection from a line in the second office to a line in the first office is completed under control of the calling party.

35 8. In a telephone system, two automatic offices and a semi-automatic office, subscribers' lines terminating at each office, a trunk line connecting the two automatic offices, a trunk line connecting one automatic office and the semi-automatic office, an operator's position at the other automatic office, means automatically operated responsive to the initiation of a call on a line terminating at said one automatic office for extending a connection over the first trunk line to said other automatic office, means controlled by the calling party for releasing said connection and for extending a connection from the calling line to a called line terminating at either said one automatic office or said semi-automatic office, means responsive to the initiation of a call on a line terminating at the semi-automatic office for extending a connection from the line over the second and first-mentioned trunk lines in series to said operator's position, and means controlled from said operator's position for extending a connection from the calling line to a called line terminating at said one automatic office and for releasing said first trunk line.

40 9. In a telephone system, three offices, subscribers' lines terminating at each office, a trunk connecting the first and second offices, a second trunk connecting the second and third offices, means responsive to the initiation of a call on a line terminating at the second office for automatically extending a connection from the line to the third office over said second trunk, subscriber-controlled means for releasing said connection and for extending a connection from the calling line to a called line in either the first or second office, means responsive to the initiation of a call on a line terminating at the first office for automatically extending a connection to the third office over said first trunk and said second trunk, means controlled from the third office for extending a connection from the calling line over the first trunk to a called line terminating at the second office and for releasing said second trunk line, and means controlled from the third office for extending a connection from the last-mentioned calling line to a called line terminating at the first office and for releasing both of said trunk lines.

45 10. A telephone system as claimed in claim 9 in which connections from lines terminating at the second office are extended by switching apparatus controlled by impulses transmitted by the calling party and in which connections from lines terminating at the first office are extended by switching apparatus controlled by impulses transmitted by an operator at the third office.

50 REINHOLD HOFERT.
EDUARD WOCHINGER.
